UNITED STATES PATENT OFFICE.

ROBERT J. BARNES, OF PHILADELPHIA, PENNSYLVANIA.

FLASK-FILLING MACHINE FOR USE IN FOUNDRIES.

Application filed September 11, 1925. Serial No. 55,782.

The object of this invention is to provide improvements generally in the method and apparatus employed in the manufacture of castings, such for instance as cast-iron 5 soil pipe, though the invention because of its wide adaptability is by no means limited to this particular line of foundry work.

Another object is to provide means for handling the usual flasks much more expeditiously than is usually possible, said flasks being mounted upon a specially constructed traveller above which is properly arranged the discharge end of a moulder's sand chute, which leads from a hopper or magazine into which it is carried by a suitable conveyor.

A further object is to provide a traveller having a preferably reciprocatory motion and capable of carrying two, or more, flasks, 20 one of which after having been filled with sand beneath the chute and removed from thereunder can be replaced by a third or by an empty flask, while the second flask upon the traveller is beneath the said chute and is receiving its supply of sand, following which stage in the operation of the device, the traveller moves into another position and the second filled flask can be replaced while the third flask is being filled.

Still another object is to provide, in conjunction with the foregoing details of construction, means to regulate the quantity or height of sand in a flask after it has been filled from the chute, means to compress the loose sand as received from said chute to a predetermined density, and means to return the surplus or spilled sand to the conveyor, which then carries it again to the hopper or magazine.

And a still further object is to provide numerous details of constructions which contribute towards the general increase in efficiency made possible with the use of this device over known apparatus employed for the same purpose, the present invention making possible the more rapid filling and tamping of a greater number of flasks by fewer operatives than are heretofore required.

With these and other objects in view, the present invention comprises additional novel details of construction and operation hereinafter fully brought out in the following description, when read in conjunction with the accompanying drawings, in which Fig. 1 is a front elevational view of one form

of the invention; Fig. 2 is an end view of the same, partly in section; Fig. 3 is a top plan view of the traveller tracks and associated elements; Fig. 4 is a side elevation 60 of the same; Fig. 5 is a side elevation of the traveller per se; and Fig. 6 is an enlarged end elevation of the track, traveller, scraper and tamping roller.

Referring to the drawings, the floor 1 of a foundry is shown and provided with a pit 2, lined in any suitable manner at 3, and having its upper and otherwise open portion covered by a suitable grating 4. Secured in any suitable manner to the upper periphery of the walls of the lining material is a hopper, comprising oppositely positioned, downwardly converging front and rear walls 5, which at their lower portions are joined by a segmental section 6, the laterally opposite sides of said hopper being inclosed by downwardly converging side walls 7, while each of the walls 5 and 7 adjacent to its lower portion merges into a vertically extending set of elements 8, which co-operate to form a support for the lower central portion of the hopper above the floor of the pit 2.

Extending upwardly from the central portion of the hopper and through the grating 4 is a casing formed between forward and rear walls 9 and oppositely positioned side walls 10, the lower portion of each of the walls 9 and 10 being partially cut away to provide apertures 11, for permitting sand which enters the hopper upon the walls 5 and 7 to gravitate toward and enter the lowermost portion 6 of the hopper at a predetermined maximum rate of flow, the effective areas of said apertures 11 being controlled by means of vertically adjustable gates 15.

Positioned within the respective upper and lower portions of the vertically extending casing 16, surrounded by the walls 9 and 10, are shafts 17, upon which are mounted suitable wheels or pulleys 18, over which passes a continuous flexible belt 19, provided with spaced buckets or the like 20, each of which buckets extends transversely the entire width of the belt. The upper portion of said casing is provided with a forwardly extending offset 21, both casing and offset having their interiors inclosed by means of a suitable cover 22, while the offset itself is open at its lower portion and leads into a diagonally ex-

tending chute 23, having pivotally mounted at its lower end 24 an angularly oscillatable nozzle 25, which is of relatively shallow cross-section from front to rear, but which in the preferred form of the device extends the full width of the casing 16 and the belt 19 inclosed therein, said nozzle being capable of being moved manually forwardly and rearwardly upon the pivots 24, as shown by the dot-and-dash lines of Fig. 2.

Mounted upon the floor 1 of the foundry and upon laterally opposite sides of the pit 2 is a run-way or track, comprising a pair of parallel I-beams or other suitable supports 26 for a corresponding number of rails 27 secured upon said beams, and upon which run the preferably grooved pulleys 28, which are rotatably mounted between pairs of oppositely positioned channel-irons 29, connected at their upper end by a platform 30 which they support, and thus form a truck or traveller, which is adapted to move to and fro upon the rails 27.

The said truck may be provided with any desired number of pairs of these grooved wheels, and as a unit appears substantially as shown in Fig. 5, the pairs of channel-irons being separated from each other, and the channel-irons of each pair being also spaced apart by means of suitable tie-rods and spacers 31. To the underside of the platform 30 is secured one or more brackets 32, a clamping means 33 being carried by each bracket for securing the latter directly to a cable 34, which passes over a pair of grooved pulleys 35 mounted upon shafts 36, which in turn are journalled in suitable bearings 37, which are mounted upon the adjacent sides of the I-beams or the like 26.

One of the shafts 36 extends forwardly at 38, and is provided with a pulley 39, which is driven in any suitable manner as for instance by a belt 40 from any suitable source of power 41, as for instance an electric motor, an internal combustion engine, or the like. The cable 34 is provided with a turnbuckle 42 or other suitable means for taking up any slack which may develop after a prolonged period of use, and for causing the cable to run in one direction and then reverse and run a predetermined distance in the opposite direction. To cause the traveller 29-30 to have a reciprocating movement, there is provided any suitable system of electric or other control from the source of power, for causing said power source to interrupt a too directional movement to said cable.

Positioned upon the opposite sides of the track or run-way from the traveller 29-30 and upon each of the laterally opposite sides of the chute-nozzles 25, is a pair of

vertically extending posts 43, suitably braced at 44 and provided at its upper end with an adjustable mechanism 45 and compression-spring 46, operating upon a journal-bearing slideable vertically in a cut-out portion 47 in each of said posts, each of said shafts journalled in said bearings provided with a roller 48 for a purpose hereinafter described. Also carried by the upper portion of the posts of each pair are laterally extending bracket members 49, between which extend diagonally positioned scraper-bars 50, which by means of bolts or any other suitable means are vertically adjustable for a purpose also hereinafter described.

Assuming that the traveller 29-30 is in the position shown in Fig. 1, a flask 51, which was placed upon said traveller when in the dot-and-dash position 52, is illustrated as being beneath the discharge end of the nozzle 25, where it receives sand from the hopper 23 by an attendant manually oscillating said nozzle forwardly and rearwardly. An empty flask 52 is placed then upon the laterally extending otherwise free end portion of the traveller as also shown in Fig. 1. The power source 41 is then set into operation so as to move the traveller in the dot-and-dash position, which removes the flask 51 from beneath the nozzle and at the same time moves the flask 52 into operative position between said nozzles. While beneath said nozzle, the flask 51 is filled with as much, or more, moulders' sand than is required, even though the flow of the sand may be regulated if desired by any suitable means, such for instance as a damper or the like 53.

Thereupon, as the flask 51 moves into the position 52, it passes beneath the vertically adjustable scraper 50, which permits only a predetermined quantity of sand to remain above the side walls of the flask, the excess sand being removed to the side and falling through the grating 4 passes into the hopper 5-7, while the remaining sand upon the flask is firmly pressed or "tamped" by and as it passes beneath the right-hand roller 48 (as viewed in Fig. 1). Similarly, after the flask 52 has been filled, its sand surplus will be regulated by the left-hand scraper 50 and adjacent roller 48.

Thus the traveller passes to and fro, and with a minimum of lost motion occupies only the attention of a man operating the nozzle 25 and power source 41, and four helpers positioned respectively upon the laterally opposite sides of each of the end portions of the run-way, one man of each pair removing a filled flask, and the other of the same pair placing upon the said traveller an empty flask, which cooperate to make the operation substantially continuous.

Having thus described my invention, what I claim and desire to protect by Letters Patent of the United States is:

1. A flask-filling mechanism, comprising the combination of a traveller having a pair of flask supporting portions, means to oscillate said traveller to and fro, a sand hopper, a chute operative to convey sand alternately towards the flask positions of said traveller, means to convey sand from said hopper to said chute, a transversely oscillatory nozzle forming an extension of said chute and operative to spread sand substantially evenly in flasks upon said traveller, as said supporting portions move into position adjacent to said nozzle, and relatively stationary, vertically adjustable means operative to smooth the sand in a flask and to predetermine the density of the resulting mold and vertically yielding rotary means to compress the smoothed sand, as said traveller moves a flask from its filling position towards a position free from said chute.
- 10 15 20 25 2. A flask-filling mechanism, comprising the combination of a traveller having a pair of flask supporting portions, means to oscillate said traveller to and fro, a sand hopper, a chute operative to convey sand alternately towards the flask positions of said traveller, means to convey sand from said hopper to said chute, a transversely oscillatory nozzle

forming an extension of said chute and operative to spread sand substantially evenly in flasks upon said traveller, as said supporting portions move into position adjacent to said nozzle, and relatively stationary, vertically adjustable means operative to smooth the sand in a flask and to predetermine the density of the resulting mold and vertically yielding rotary means to compress the smoothed sand, as said traveller moves a flask from its filling position towards a position free from said chute.

3. A flask-filling mechanism, comprising the combination of a traveller adapted to support a flask, means to supply sand to a flask upon said traveller when in one position, adjustable means to remove from said flask all over a predetermined quantity of sand from said flask as said traveller moves from said first position to predetermine the density of the resulting mold, and means to compress the sand in said flask.

In testimony whereof I have affixed my signature.

ROBERT J. BARNES.
